PULL TAB FOR TEAR STRIP OPENER

James E. Kennedy, St. Louis, Mo., assignor to Container Corporation of America, Chicago, Ill., a corporation of Delaware

Filed Sept. 18, 1968, Ser. No. 13,593

Term of patent 14 years

Int. Cl. D9—99

U.S. Cl. D9—256

FIG.1

FIG.2

FIG.3

FIG.4

FIG.5

FIG. 1 is a bottom plan view of a pull tab for a tear strip opener showing my new design;

FIG. 2 is an enlarged side elevational view thereof;

FIG. 3 is an elevational view looking from the right of FIG. 2;

FIG. 4 is an elevational view looking from the left of FIG. 2; and

FIG. 5 is a bottom perspective view thereof on a reduced scale.

I claim:

The ornamental design for a pull tab for tear strip opener, as shown and described.
